(57) **CLAIM**

I claim an ornamental design for a nose piece for a tool for binding band, as shown and described.

DESCRIPTION

FIG. 1 is a perspective view of a nose piece for a tool for binding band, embodying my new design;

FIG. 2 is an alternative perspective view thereof;

FIG. 3 is a left elevation view thereof;

FIG. 4 is a right elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines portions of the tool for binding band form no part of the claimed design.
